UNITED STATES PATENT OFFICE.

GEORGE G. HUNT, OF BRISTOL STATION, ASSIGNOR OF ONE-HALF TO THE PLANO MANUFACTURING COMPANY, OF PLANO, ILLINOIS.

GRAIN-BINDER.

SPECIFICATION forming part of Letters Patent No. 339,988, dated April 13, 1886.

Application filed May 18, 1883. Serial No. 95,342. (Model.)

To all whom it may concern:

Be it known that I, GEORGE G. HUNT, a citizen of the United States, residing at Bristol Station, in the county of Kendall and State of Illinois, have invented certain new and useful Improvements in Grain-Binders, which are fully set forth in the following specification, reference being had to the accompanying drawings, in which—

10 Figure 1 represents a front elevation of a portion of a harvester with my improved grain-binder applied; Fig. 2, a detail elevation of the trip mechanism on an enlarged scale; Fig. 3, an elevation of the harvester, on the stubble side thereof, showing the binder on the same scale as Fig. 1; Fig. 4, a detail section taken on the line $z z$ in Fig. 3; Fig. 5, a detail section taken on the line $x x$ in Fig. 3; Fig. 6, an elevation of the operating cam-wheel detached and on 15 an enlarged scale; Fig. 7, a detail front elevation of the breast-plate on the same scale; Fig. 8, a detail plan of the plunger-bolt and cord-holder on the same scale; Fig. 9, a perspective view of the cutter-bar and cutter on 20 a still more enlarged scale; Fig. 10, a perspective view of the tucker detached on the same scale; Fig. 11, front and edge elevations of the bracket in which the upper end of the butt-adjuster is mounted on the same scale as 25 Fig. 7; Fig. 12, a detail section taken on the line $y y$ in Fig. 1 on the same scale; Fig. 13, an end elevation showing the gear-train between the driving-shaft and main gear of the binder, and Fig. 14 a plan section taken on 30 the line $v v$, Fig. 13.

35 My invention relates to harvesting-machines which are provided with automatic grain-binders, and especially that class of grain-binders in which cord is used for the band material.

40 The invention consists in certain specific improvements in various parts of the machine, and I will proceed to describe in detail the construction and operation of so much of the machine as is necessary to a full and complete 45 understanding of my present improvements, and will then point out definitely in the claims the particular features which I believe to be new and desire to protect by Letters Patent.

50 In nearly all of its general features the harvesting-machine may be of any ordinary con-

struction, and therefore I have not shown a full and complete machine in the drawings, and shall not here describe in detail all the parts which are necessary to a complete working machine, but shall only describe those parts which are necessary to an understanding of the construction and application of my present improvements.

55 In the drawings, A represents a portion of the main frame of the harvester at the outer or stubble side of the machine where the binder is located, a the elevator-frame, and A' the usual main supporting-wheel. The crank-shaft B, which drives the cutters, is here shown as arranged outside of the supporting-wheel, 60 and by means of a sprocket-wheel, b , and drive-chain b' motion is communicated from this crank-shaft to the main drive-shaft C of the binder, which is provided with a sprocket-wheel, c , to which the said chain is applied.

65 The binder is of a well-known type of the class provided with an automatic tripping mechanism when the bundle has reached a certain size, and many of the features of this 70 mechanism are so well known as not to require description here; hence I shall restrict the description to those parts which I have improved, referring to such common and well-known parts of the mechanism as may be necessary.

75 There is a great tendency in these harvesting-machines with binders to sag, especially inside of the main supporting-wheel. To counteract this, I mount a bracket, D, on the end 80 of the main frame outside of the main wheel. This bracket extends from the lower cross-beam to the beam above, as shown in Fig. 3 of the drawings. On the inside of this bracket is a stud or projection, d , and a truss-rod, d' , 85 is passed over this projection and then extended outward to the front and rear corners of the main frame, to which its respective ends are attached. In this way I obtain a supporting-truss which also resists the inward strain, 90 because its end attachments are considerably outside the vertical plane of its central support, so that the truss resists not only a vertical thrust, but also a lateral one to a very considerable extent, as shown in Fig. 14 of the 95 drawings.

100 The drive-shaft C of the binder is provided

with a clutch and pinion, C', common to this class of machines, the clutch having the usual arm, e', against which the stop-arm acts to throw the binder out of operation. What has 5 heretofore constituted the stop-arm E and crank-arm to which the operating-pitman is attached I make in two separate pieces, e and e', the first of which is properly the stop arm, and is mounted loosely on the shaft, while the 10 second, e', is rigidly attached to the same shaft and is connected to the main pitman f. The loose arm e is arranged above the journal of the first gear of the train connecting the pinion C' with the main gear-wheel F, and a lever, 15 G, is pivoted at its upper end to this same journal, from which it extends downward and outward underneath the arm, as shown in Fig. 2 of the drawings, being curved at its outer end. A set-screw, g, is inserted in this lever, 20 being arranged so that the end will strike the under side of the arm e, whereby the distance between the lever and this arm may be adjusted. An eyebolt, G', is also pivoted on the same journal as the lever, and is thence extended up through an opening in the arm e, 25 and is surrounded by a spiral spring, g', above the stop-arm, being provided with a nut, g'', on its upper end, by means of which this spring is held in place and adjusted.

30 The compressor-shaft H is arranged as usual, and an elastic pitman, h, is connected thereto by the crank-arm H', as usual, the upper end of the pitman being connected to the main gear-wheel in the usual way, and arranged 35 and operated as usual, so that further description is not necessary here. The crank-arm H' is, however, provided with a tail-piece or projection, h', extending beyond the compressor-shaft directly under the curved end of the lever G, being provided with a small roller, h'', which works against the said lever. The trip 40 I is mounted on a hinged support, i, in a well-known way, the latter being connected by a link, i, and crank-arm i' to the compressor-shaft H. Now, it will be seen that as the grain is accumulated against the trip by the packers the latter will yield, as usual, thereby oscillating the compressor-shaft, which will lift the end of the lever G and thereby lift the 45 stop-arm against the spiral spring arranged above it, until finally it is disengaged from the clutch-arm and the binding mechanism is set in motion. The automatic trip mechanism is therefore in this instance operated from 50 the trip through the compressor-shaft and in connection with the usual compressing devices, thereby obviating the employment of a special shaft and devices for this purpose.

When the compressing devices have operated as usual and return to their nominal position, the stop-arm will be set in position at the proper time to engage with the clutch-arm in the usual way, and will be held in this place and compelled to engage with the 55 clutch-arm by means of the spring above it. The set-screw in the lever permits an adjustment of the latter in relation to the stop-arm

so as to secure a perfect working of the parts at all times and to compensate for any wear or imperfection in construction of these parts. 70

The main gear-wheel F of the binding mechanism is mounted on the usual main shaft, f', and on the inner portion of this shaft is a wheel, J, in the usual position of the cam-wheel of this class of binders, where only a 75 single cam and gear wheel is used. This wheel J in this instance, however, is simply provided with a short gear section or sections, j, arranged to give the required revolution or revolutions to the knotting-hook. The cam-wheel K is mounted on this shaft, near the inner end thereof, and, as shown in the drawings, is of skeleton form and dishing in shape. The outer rim, k, of this wheel is of irregular 80 form, as shown in Fig. 6 of the drawings, and acts as a cam for the purpose of reciprocating 85 the bar which operates the tucker and cutter, as will be presently described. Inside of this rim, on the face of the wheel, is a camway, k', which is a simple flat surface plain all the 90 way round, except at one point, where it has a sharp projection or crown, k''. On the inside of the cam-rim k at a certain point is a short stud or projection, k'', as shown in Fig. 6 of the drawings. 95

The cord-holding device is composed of a notched disk, M, and a grooved plate or keeper, M', which is pivoted at the inner end, m, and is provided with a spring, m', at its back to hold it in its place. The notched disk 100 is also provided with a ratchet-wheel, m'', with which a pawl engages to give the required intermittent motion to the disk. These parts just mentioned are of the ordinary construction, except the pawl, and need no further description. 105

In most machines of this type the plunger-bolt N is employed to turn the notched disk. I have devised some improvements, however, in the mode of accomplishing this result. 110 The plunger-bolt is provided with a spiral spring, n, as usual, which operates to force it outward and hold its outer end, which is provided with a roller, n', against the camway k''. The dog or pawl O is pivoted at its inner end 115 to the bent arm or bracket O', which at its other end is hung on the plunger-bolt between the end of the spiral spring and a collar, n''. A suitable spring, o, is provided, by means of 120 which the pawl is held to engage with the ratchet on the notched disk. From the construction and arrangement of these parts, as shown in Fig. 8 of the drawings, it will be seen that, whenever the cam or projection k'' is brought against the end of the plunger-bolt 125 the latter will be forced inward, carrying with it the arm O' and the pawl O, and thus give a partial turn to the notched disk. The arrangement of these parts is such that the action of the pawl is nearly direct upon the 130 ratchet, and it will be seen that there is yielding not only of the pawl on its direct support, but also of that support on the plunger-bolt, so that the pawl follows the ratchet with cer-

tainty, and there is no danger of failure in action. It will also be seen that this device is very simple in construction and is composed of very few parts.

5 A bar, P, is mounted on the lower portion of the breast-plate Q, being held in suitable ways, q, which permit it to slide back and forth across the opening in the breast-plate through which the cord passes. To this bar 10 is attached the cord guide and stripper p and the cutter p', as shown in Figs. 7 and 9 of the drawings. Near one end of the bar are two pins, p'', which are arranged to receive between them the cam-rim k of the wheel K. On the 15 back of the bar, just inside of the pins, there is also a recess or shallow notch, p''. The tucker R is pivoted to the breast-plate, and is provided with two lugs, r r', projecting from its journal, as shown in Fig. 10 of the drawings, 20 the former being shorter than the latter, and arranged to enter the notch p'' in the sliding bar, as shown in Fig. 7 of the drawings. Now the cam-rim k is so constructed as to give the required reciprocating movement to 25 this sliding bar as it revolves between the pins thereon, and in the process of binding the first movement of the bar is in the direction of the arrow in Fig. 7 of the drawings, whereby the guide carries the cord inward in 30 the proper position to be taken by the hook, and the tucker is thrown down, the projection r turning out of the notch. The bar is held in this position until the knot is formed, and the band is required to be cut, when a still 35 further movement is made in the same direction, thereby bringing the cutter into action, when the bar is reciprocated in the opposite direction and the tucker is thrown up, this latter operation being assisted by the projection k' on the cam-rim coming in contact with the lug r' on the tucker.

I provide a bracket, S, in which the butt-adjuster S' is mounted. This bracket is angular in form, as shown in Fig. 11 of the drawings, and is mounted on the upper elevator-shaft, which passes through an aperture, s, therein, the bracket being fastened to the side of the elevator-frame. The upper branch 45 of this bracket contains simply a journal-bearing for the upper end of the shaft, s', of the butt-adjuster. The lower branch has at its end a socket-bearing, s'', for the lower end of this same shaft, on which is fixed a bevel-pinion, s''. The bracket is also provided at 50 its end with a spindle, s', set therein and projecting out at one side, on which is mounted a short shaft, S', having at one end a bevel-pinion, s', which engages with the corresponding pinion on the adjuster-shaft, and at the 55 other end the pinion s'', which gears with the corresponding pinion on the elevator-shaft, from which motion is communicated to the apron of the butt-adjuster.

The slatted apron S' of the butt-adjuster 60 runs around the upper shaft, s', by which motion is communicated to it and the lower shaft and a lower journal, s', which is mounted in and

between the branches of a forked support, V. The stem of this support, v, is turned down at its upper end somewhat, and passes through 70 a cross-bar, v', in the frame of the adjuster, and at its upper end is inserted in an aperture in a similar cross-bar, v'', between which and the enlarged portion of the stem it is surrounded by a spiral spring, v''. The arms v' 75 of the fork of this support are set in suitable grooves in the upper and lower pieces of the frame, so as to permit a sliding or lengthwise movement of this support. It will thus be seen that the lower journal of the apron is 80 yielding to accommodate any change in the canvas of the apron, and at the same time the tension on the latter will always be preserved to the required degree by the operation of the spring. 85

I also provide an apron or grain-guard, T, which I hinge at its upper edge to the upper part of the elevator-frame, from which it projects downward and outward over the incline to which the grain is delivered. A 90 hand-lever, t, is attached to this apron and arranged within reach of the driver, so that he may adjust it at will, and any suitable device may be provided for fastening the apron in any desired position. In this instance I 95 provide a series of pins, t', near the end of the lever, which passes through a link, t'', and the apron is held in any desired position by adjusting the link over one or another of the pins. A keeper, T', may be pivoted to the 100 lever, so as to swing over the top of the pins to prevent disengagement of the link, if desired.

In the usual arrangement of the gear-train between the pinion on the main drive-shaft 105 of the machine and the main gear-wheel of the binder the gears are all of one size and provided with the same number of teeth, and have a certain relation to the main wheel, so that they stop at the same tooth with each 110 revolution of the latter. The wear is therefore greater at this point than any other, and there will soon be some looseness between the gears, so as to occasion some inaccuracy in the action of the stop-arm. To avoid this, I make 115 the gears of this train with a different number of teeth, so as to break up the regularity of the stopping place. In the drawings, I have shown four gears in this train, U U' U'' U''', commencing at the driving pinion. The first 120 and last of these in this instance, as shown in Fig. 13 of the drawings, are provided with fifteen teeth, while the two middle ones have only fourteen, which construction and arrangement will obviously break up the regularity 125 of the stopping-places mentioned above.

I have described the operation of the several parts of my invention in connection with the description of their construction and arrangement, so that it is not necessary to give 130 another statement of the entire operation of binding a bundle. It will be understood, however, that the devices described are timed in relation to each other and in relation to

the other parts of the binder, so that the usual well known steps in the process of forming a bundle, binding, and discharging it in this class of machines will be performed in their 5 usual and required order.

I do not wish to be understood as limiting myself to the precise construction and arrangement of all the devices as herein described and shown, for they may be modified 10 to some extent and still retain the gist of my invention. It is also obvious that these devices are not all necessary to each other in the same machine; but some of them may be applied in connection with other different devices 15 for performing the functions of those with which they are here associated.

Having thus described my invention, what I claim as new, and wish to protect by Letters Patent, is—

- 20 1. The main frame, in combination with a truss-rod at the binder end of the frame, and a central support for the latter arranged in a vertical plane inside of the vertical plane passing through the terminal attachments thereof, substantially as and for the purposes set forth.
- 25 2. The main frame, in combination with the truss-rod d' , attached at its ends to the front and rear corners of the frame, and the bracket D , provided with a stud, d , over which the truss-rod passes and arranged in a vertical plane inside of a vertical plane passing through the end fastenings of said rod, substantially as and for the purposes set forth.
- 30 3. The stop-arm e , in combination with the lever G , the compressor-shaft H , the crank-arm H' , provided with a projection, h' , and the trip connected to the compressor-shaft, substantially as and for the purposes set forth.
- 35 4. The stop-arm e , in combination with the lever G , the adjusting set-screw g , and the crank-arm H' , provided with the projection h' , substantially as and for the purposes set forth.
- 40 5. The stop-arm e , independent of the crank-arm e' , in combination with the lever G , eye-bolt G' , mounted on a pivot fixed upon the main frame, spring g' , and adjusting-nut g'' , substantially as and for the purposes set forth.
- 45 6. The stop-arm e , in combination with the lever G , eye-bolt G' , mounted on the journal of said lever, spring g' , adjusting-screw g , compressor-shaft H , crank-arm H' , and trip I , connected to the compressor-shaft, all constructed and operating substantially as and for the purposes set forth.
- 50 7. The cord-holding disk M , in combination with the plunger-bolt N , arm O' , attached to the bolt and carried thereby, and the spring-pawl O , pivoted to said arm, substantially as and for the purposes set forth.
- 55 8. The cam-wheel K , provided with the camway k' , having a projection, k^2 , in combination with the plunger-bolt N , spring n , and pawl O , substantially as and for the purpose set forth.

9. The sliding bar mounted in suitable ways, in combination with cam-wheel K , arranged to act directly to reciprocate said bar, and the tucker adapted to be operated positively by 70 the reciprocation of the said bar, substantially as described.

10. The sliding bar mounted in suitable ways, in combination with the cutter and cord guide and stripper, both mounted thereon, 75 the tucker adapted to be operated by the sliding bar, and mechanism for reciprocating said bar, whereby the guide and stripper, cutter and tucker are all operated positively, substantially as described. 8c

11. The cam-wheel K , provided with the cam-rim k , in combination with the sliding bar P , mounted at the lower part of the breast-plate and provided with pins p^1 and notch p^2 , and the tucker R , provided with a 85 lug, r , arranged to engage with the notch in the bar, substantially as and for the purposes set forth.

12. The cam-wheel K , provided with the cam-rim k , and the stud k' , in combination 90 with the sliding bar P , provided with pins p^1 and notch p^2 , and the tucker R , provided with two lugs, $r r'$, substantially as and for the purpose set forth.

13. The cam-wheel K , provided with a cam- 95 rim, k , and stud k' , in combination with the sliding bar P , provided with pins p^1 and notch p^2 , the tucker R , and the guide and stripper p , and cutter p' , both attached to the bar, substantially as and for the purpose set 100 forth.

14. The angular bracket S , in combination with the driving-shaft s' of the butt-adjuster mounted in the two arms of the bracket, the bevel-pinion s^3 on the shaft, the shaft S^1 , 105 mounted on the spindle of said bracket and provided with pinions $s^4 s^5$, and the elevator-shaft provided with a pinion engaging with the pinion s^6 , all constructed and operating substantially as and for the purpose set forth. 110

15. The grain-guard T , hinged at its upper edge to a suitable support, in combination with a lever, t , whereby it may be adjusted by the driver, substantially as described.

16. The hinged grain-guard T , in combination with the lever t , provided with pins t' , and the link t' , substantially as and for the purposes set forth. 115

17. The main driving-pinion C , in combination with the main gear-wheel F of the binding 120 mechanism, and a train of gears, $U U' U'' U'$, the first and last of the train having the same number of teeth, and the two middle ones having the same number of teeth but differing in number from the two former, substantially as and for the purposes set forth. 125
